(57) **CLAIM**

The ornamental design for a faceted glassware, as shown and described.

DESCRIPTION

FIG. 1 is a top perspective view of a faceted glassware showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines in the drawing depict portions of the faceted glassware that form no part of the claimed design.
